DESIGN FOR A HAT

William Getman, New York, and Morris Meisels,
Bronx, N. Y.

Application March 29, 1938, Serial No. 76,156

Term of patent 3½ years

To all whom it may concern:

Be it known that William Getman and Morris Meisels, citizens of the United States, William Getman being a resident of Manhattan, in the county of New York and State of New York, and Morris Meisels being a resident of the Bronx, in the county of the Bronx and State of New York, have invented a new, original, and ornamental Design for a Hat, of which the following is a full, clear, and exact description, reference being had to the accompanying drawing, forming part thereof.

Fig. 1 is a perspective view seen from the front of a hat, showing the new design.

Fig. 2 is a back elevational view of Fig. 1.

The characteristic feature of our design for an open hat resides in the combination of the bows and ties on the hat, as shown.

We claim:—

The ornamental design for a hat, as shown and described.

WILLIAM GETMAN.
MORRIS MEISELS.
